UNITED STATES PATENT OFFICE.

DULON F. BUCHMILLER AND ERNEST SCHWARZ, OF LANCASTER, PENNSYLVANIA, ASSIGNORS TO THE SAFE PADLOCK AND HARDWARE COMPANY, A CORPORATION OF PENNSYLVANIA.

DESIGN FOR A HAT AND COAT HANGER.

41,006.

Specification for Design.

Patented Nov. 29, 1910.

Application filed September 29, 1910. Serial No. 584,582. Term of patent 3½ years.

To all whom it may concern:

Be it known that we, DULON F. BUCHMILLER and ERNEST SCHWARZ, citizens of the United States, residing at Lancaster, in the county of Lancaster and State of Pennsylvania, have invented a new, original, and ornamental Design for Hat and Coat Hanger, of which the following is a specification, reference being had to the accompanying drawings, forming a part thereof.

Figure 1, is a front elevation of our hat and coat hanger. Fig. 2, is a side elevation of the same.

We claim:

The ornamental design for a hat and coat hanger, as shown.

In testimony whereof we affix our signatures in presence of two witnesses.

DULON F. BUCHMILLER.
ERNEST SCHWARZ.

Witnesses:

Wm. J. COULTER,
JOHN J. THOMPSON.
